UNITED STATES PATENT OFFICE.

DAMON W. BROCKWAY, OF DOVER, MAINE.

SHAWL-STRAP.

SPECIFICATION forming part of Letters Patent No. 398,125, dated February 19, 1889.

Application filed December 28, 1888. Serial No. 294,841. (No model.)

To all whom it may concern:

Be it known that I, DAMON W. BROCKWAY, of Dover, in the county of Piscataquis and State of Maine, have invented certain new and useful Improvements in Shawl-Straps, of which the following, taken in connection with the accompanying drawings, is a specification.

My invention relates to shawl-straps for carrying bundles of clothing or other articles; and it consists in certain novel features of construction, arrangement, and combination of parts, which will be readily understood by reference to the description of drawings and to the claims to be hereinafter given, and in which my invention is clearly pointed out.

Figure 1 of the drawings is a perspective view illustrating my invention as applied to a shawl or wrap. Fig. 2 is a sectional elevation of my improved shawl-strap, the handle and the central portion of the base rod or bar being cut in section, while the end portions are shown in elevation and the straps for encircling the bundle being omitted; and Fig. 3 is a transverse section through the base rod or bar on line $x x$ on Fig. 2, and showing a portion of one of the bundle-encircling straps and its buckle in elevation.

In the drawings, A is the base rod or bar composed of the parts a and $a' a'$, made circular in cross-section and connected together by means of a dowel or tenon, b , formed upon one of the parts and entering a socket formed in the end of another part, as shown in Fig. 2, and in which it is secured by glue or other suitable adhesive material.

B is the handle, made, preferably, of two thicknesses of leather sewed together, though it may be made of a single thickness of leather or of metal, if desired, said handle having formed in each end thereof a hole, through which the dowel-pin b passes before entering the hole in the part a of the base-rod A, as shown.

The parts $a' a'$ have turned therein an annular groove, c , to receive the bundle-encircling straps C, which are passed around said base-rod A, within said groove c , in the form of a loop, d , and the end of the portion passed around said rod is secured to the main body of the strap by a rivet, e , as shown; or it may be sewed thereto, if preferred, the buckle f

being applied to said loop upon the side of the rod A opposite to the point where the end is secured to the main body of the strap, with 55 its central or tongue-supporting bar between said rod and the surrounding loop of the strap.

The base-rod A may be made of metal, if desired; but I prefer to make it of a close-grained hard wood turned in a lathe to a circular form; and the dowel-pins or tenons b may be formed upon the parts $a' a'$ and the sockets in the part a , as shown; or the dowels or tenons may be formed upon the part a 65 and the sockets in the parts $a' a'$, or sockets may be formed in all the parts and the dowels made separate, without affecting the principles of my invention. The part or parts in which the sockets are formed are re-enforced 70 or strengthened by metal ferrules g , applied thereto to prevent the splitting of the parts by the insertion of the dowels or tenons therein.

When the base-rod A is made of wood, I 75 stain or color its outer surface to match the color of the leather straps and handle.

The advantages of this construction are great stiffness and rigidity of the base-rod, coupled with comparative lightness of the 80 same, cheapness of construction, and durability.

What I claim as new, and desire to secure by Letters Patent of the United States, is—

1. In a shawl-strap, the combination, with 85 the bundle-inclosing straps and a handle, of a base-rod circular in cross-section, made in three parts, arranged end to end, and connected together by dowel-pins or tenons and sockets, and provided with circumferential 90 grooves to receive the bundle-inclosing straps, and having spaces between the ends or shoulders of the several parts to receive the ends of the handle.

2. In a shawl-strap, the combination of a 95 base-rod composed of three parts arranged end to end and connected together by dowel-pins or tenons and sockets, a plurality of bundle-inclosing straps secured in fixed positions longitudinally on said base-rod, and a bent 100 handle having a hole in each end, through which the dowel-pins or tenons pass to connect said handle and rod.

3. In a shawl-strap, the combination of a

base-rod made circular in cross-section and provided with a plurality of annular grooves, a plurality of bundle-encircling straps, each having one end thereof wrapped around said rod in one of said grooves, with the end secured to the main body of said strap, thus forming a loop freely movable about said rod, and a buckle attached to the looped end of each of said straps and held in place by having its bar confined between said rod and the surrounding loop of the strap.

In testimony whereof I have signed my name to this specification, in the presence of two subscribing witnesses, on this 20th day of December, A. D. 1888.

DAMON W. BROCKWAY.
